United States Patent Office

Des. 203,133
Patented Dec. 7, 1965

203,133

STUD TRACK

Michael C. Senek and John L. Leifer, Warren, Ohio, assignors to The Bostwick Steel Lath Company, Niles, Ohio, a corporation of Ohio

Filed Apr. 2, 1965, Ser. No. 84,585

Term of patent 14 years

(Cl. D54—1)

Fig. 1

Fig. 2

Fig. 3

FIGURE 1 is a top perspective view of a portion of a stud track, embodying our new design.

FIGURE 2 is an end elevation of the stud track shown in FIGURE 1.

FIGURE 3 is a top plan view of the stud track shown in FIGURE 1, shown broken away for indeterminate length and convenience of illustration.

We claim:

The ornamental design for a stud track, as shown.
